(57) **CLAIM**

The ornamental design for a trunk lid, as shown and described.

DESCRIPTION

FIG. 1 is an environmental perspective view of a trunk lid showing my new design;

FIG. 2 is a front elevational view, with the rear being a mirror image, thereof;

FIG. 3 is a right side elevational view, with the left side being a mirror image, thereof;

FIG. 4 is a top view thereof; and,

FIG. 5 is a bottom view thereof.

The broken line showing of the hardware, the leather straps, and the trunk body in FIG. 1 is for illustrative purposes only and forms no part of the claimed design.
